UNITED STATES PATENT OFFICE.

ISIDORE DITESHEIM, OF LA CHAUX-DE-FONDS, SWITZERLAND, ASSIGNOR TO FA-BRIQUES MOVADO, OF LA CHAUX-DE-FONDS, SWITZERLAND.

WINDING DEVICE FOR TIMEPIECES.

Application filed December 3, 1927, Serial No. 237,534, and in Switzerland September 6, 1927.

This invention relates to a time piece, for example a necklace watch, an alarm clock or any other portable or stationary instrument, comprising a clock work whose main spring is wound by means of a winding stem adapted to rotate on itself and the action of which is effective only when the stem is rotated in one direction, while having no effect if rotated in the opposite direction. 5 The invention is particularly applicable to wrist watches and other time pieces of small dimensions where the winding and setting operations are difficult by reason of the small dimensions of the winding head mounted on 10 the winding stem, and which is difficult to grasp, particularly by a gloved hand. 15

Endeavor has been made in the past to eliminate this defect in round watches by means of a rotating and toothed bezel collar which engages in a pinion of the winding stem, but this method cannot be used practically in watches of rectangular, oval or other form differing from the round form. 20

In the time piece forming the subject of 25 the present invention the problem has been solved by means comprising at least one rack intended to engage in a toothed portion or denture of the winding stem and communicate to this latter a movement of rotation 30 about its own axis, said rack being controlled by a reciprocating element of the case containing the clock work, in such manner that the rack becomes disengaged from the denture of the winding stem toward 35 the end of its stroke, while the control member moves in a direction of its reciprocatory movement. These specific characteristics of the invention may be realized by different forms of construction according to the 40 desire of the maker and the type and form of the time piece.

A rectangular watch having two racks to control or drive the winding stem is shown on the accompanying drawing by way of example. 45

Figure 1 is a front elevation showing the parts in normal state.

Figure 2 is a similar but partial view showing the racks in position during operation. 50

Figure 3 is an enlarged section on line III-III of Figure 1.

Figure 4 is an enlarged section on line IV-IV of Figure 3.

Figure 5 is an enlarged section on line V-V 55 of Figure 3.

The rectangular watch shown comprises a movement 1 which is mounted in a case having a support or frame 2, a back or end 3, and a bezel 4 carrying the crystal 5. The end 3 and the bezel 4 are attached as usual to the support 2, each by a notch adjustment. The dial is designated by 6. 60

The winding stem 7 passes through the frame 2 and controls the winding and traction operated setting mechanism, which are of usual construction. It is surmounted by the winding head 8 and comprises a pinion 9 placed directly below the head 8. The winding stem acts on the winding mechanism only when rotated in one direction; in the other direction the action of stem 7 has no effect. It is different when traction is exerted on stem 7 drawing it out and bringing it into position for setting the hands, in which position stem 7 acts on the setting mechanism when rotated in both directions. Engaging in pinion 9 are two racks 10, 11 arranged tangentially to the pinion and on either side thereof. Each rack is slidably retained in grooves 12 and 13 of the frame and each 75 racks attached to a slide 14 and 15, by means of transverse rods 16 and 17. The slides 14 and 15 are of inverted channel section and have their free ends formed with flanges slidably retained in grooves 18, 19 of the 80 frame 2. The rods 16 and 17 intersect the space within the channelled slides, being anchored in the opposite sides thereof. The slides 14 and 15 are arranged at either side of head 8 symmetrically with respect to the 85 winding stem, so that they may be brought closer to or separated from each other, as shown on Figures 1 and 2, and, being hollow like a trough and exactly similar, they constitute elements of the case of 90

which they form one of the sides when their inner ends are in abutment (Figure 1). The outer ends of the slides are formed as a knob 21 by means of which the slides may easily be grasped and actuated manually. When the slides are united they entirely cover the winding head 8, which is thus hidden within the casing. The joint 22 separating the two slides being scarcely visible, these latter appear to be an integral part of the case, and in order to strengthen this illusion the case is formed on the side opposite the winding head with sham slides, 14', 15' so that the two sides thereof have a similar appearance. 95

When the slides 14, 15 are separated from each other, as shown on Figure 2, the racks 10 and 11 move in opposite directions, relatively, and communicate rotary movement 5 to pinion 9 and to the winding stem. It is the same when the slides are pushed toward each other, so that it is possible to wind the main spring of the watch by communicating repeated reciprocatory movements to slides 10 14 and 15 in both directions. However, the extent of separation of the slides and of the racks 10, 11 is limited by stops 23 and 24 against which the transverse rods 16 and 17, which pass through perforated lugs of the 15 racks, strike.

The stops 23, 24 prevent the slides from coming out of their respective guide grooves 18, 19 and thus becoming loosened from the watch. They are mounted so that the winding 20 head will be entirely uncovered when the transverse rods 16, 17 strike against blocks 23, 24 which permits of grasping the winding head drawing it slightly outwardly and setting the watch.

25 This operation is made possible by the fact that the dentures of racks 10 and 11 disengage from pinion 9 when the slides approach stops 23, 24; the racks again engage the pinion as soon as they begin their return stroke.

30 It is apparent that the invention is applicable not only to rectangular watches as shown, but also to watches or clocks of round, oval or any other form differing from the rectangular form.

35 The construction of these modifications presents no difficulty for one skilled in the art, since the constructive problem consists simply in adapting the form and movement of the rack or racks (if there are two) to the

form of the time piece. Thus, the rack may 40 have a curved form or may be a pivoted toothed sector and mounted on a round or curved time piece. In such case the rack may be controlled by means of a bolt or pin mounted on the support or back of the case. 45

What I desire to secure by Letters Patent is:—

1. A time piece comprising a movement and winding stem, and a casing within which said movement is mounted, an operating head on said winding stem, a pinion on said stem below said head, oppositely reciprocable racks adapted to engage said pinion for rotating said stem alternately in opposite directions, complementary channelled 55 slides slidably retained by said casing, and housing said operating head within the channels thereof, when positioned in normal abutment, said slides being operatively connected to said racks, means limiting the 60 range of movement of said slides in a direction away from one another, said slides and racks being so correlated that said racks are disengaged from said pinion when said slides are in their outermost position. 65

2. A time piece including a movement and winding stem and a rectangular casing within which said movement is mounted, the side of said casing adjacent the winding stem being provided with complementary rectilinearly reciprocable slides, symmetrical with respect to said winding stem and housing the latter when in abutment, means for rotating said stem, said slides being operatively connected with said rotating means. 70 75

In testimony whereof I have signed my name to this specification.

ISIDORE DITESHEIM.
